UNITED STATES PATENT OFFICE.

WM. H. GUILD AND WM. F. GARRISON, OF BROOKLYN, NEW YORK.

OPERATING VALVES IN DIRECT-ACTING STEAM-ENGINES.

Specification forming part of Letters Patent No. 12,592, dated March 27, 1855; Reissued July 29, 1856, No. 382.

To all whom it may concern:

Be it known that we, WILLIAM H. GUILD and WILLIAM F. GARRISON, of the city of Brooklyn, in the county of Kings and State 5 of New York, have invented a new and useful Improvement in the Means of Operating the Valves of Direct-Action Steam-Engines; and we do hereby declare that the following is a full, clear, and exact description of the 10 same, reference being had to the accompanying drawings, forming part of this specification, in which—

Figure 1, is a longitudinal central section of a direct action steam engine with our invention applied, and Fig. 2, is a face view 15 of the valve.

Similar letters of reference indicate corresponding parts in both figures.

This invention consists in certain novel 20 simple and effective means whereby the valve is caused as the stroke of the piston terminates in either direction, to have suddenly imparted to it the necessary movement to effect the return of the piston, the 25 same means serving also to relieve the valve of all unnecessary pressure and friction upon its seat.

A, is the steam cylinder having the steam ports *a*, *a'*, an exhaust port *b*, arranged in 30 the usual way in the valve seat.

B is the valve consisting of a plate which is placed parallel on its face and back, and is made with three openings as shown in Fig. 2, which are so divided that the space 35 between the outer edge of either of the outer openings *c*, and that edge of the central opening *d*, which is farthest therefrom will just include one steam port and the exhaust port in the valve seat. C, is a cap placed 40 on the back of the valve and faced to fit thereto. This cap has its ends *d'*, *d''*, lapsing over the ends of the valve, and the space between these two overlapping ends should exceed the length of the valve by 45 about the required length of stroke of the valve. It has cast with it or otherwise firmly secured to it a cylinder D, which is bored truly perpendicularly to the valve face to receive a piston E, which fits to 50 work steam tight therein and which is supported upon the point of a rocking arm *e*, which rocks on an arbor or rockshaft *f*, working on fixed bearings placed centrally within the exhaust cavity of the valve seat, 55 and passing through an opening *g*, made

through the bottom of the cylinder D. This piston has its upper or back side exposed to the pressure of the steam in the steam chest. The cap C, is confined to the back of the valve only by the pressure of steam in 60 the steam chest. It is connected with the valve rod *h*, which when the piston has arrived at a distance from the end of its stroke equal to about twice the required movement of the valve, is moved by a tappet arm *i*, on the piston rod striking one of its nuts or fixed collars *k*, *k'*. The valve seat has two cavities *j*, *j'*, outside the steam ports *a*, *a'*, to allow the steam to pass under 65 the ends of the valve to the steam ports. 70

When the engine piston arrives near the end of its stroke and the tappet arm on its rod strikes one of the nuts on the valve rod it causes the cap to slide over the back of the valve some distance before moving the 75 valve, and by the time the end *d'* or *d''*, has come in contact with the end of the valve to commence moving it on its seat, the arm *e*, passes its line of culmination and the pressure of the steam which is always acting 80 upon the piston E, to force it toward the valve then causes the arm *e*, to be thrown suddenly over giving the piston E, cylinder D, and cap C, all a quick movement to reverse the position of the valve. This will be 85 better understood by reference to Fig. 1 where the valve is represented in black outline at the left hand end of its stroke and the cap C, cylinder E and piston are represented at the same end of their stroke in 90 blue outline, the port *a* taking steam and the port *a'* exhausting. The engine piston is shown in blue to have arrived near the end of its stroke and the tappet arm *i* to be just coming into operation. The tappet moves the cap C, to the left till it arrives in the position shown in black when the arm *e*, having passed its line of culmination allows the pressure of the steam on the piston F, to throw the piston and cap to the position 95 shown in red outline where it is stopped by the cap striking the end of the steam chest. This movement from the black to the red position reverses the valve, opening the port *a'* to the steam and *a* to the exhaust ready 100 for the piston to commence its return. A similar operation takes place at the opposite end of the stroke of the piston returning the valve to the position shown in black and the other parts to the position shown in blue. 105 110

It will be understood that the piston E, takes so much of the pressure off the back of the valve as is due to its area, and the pressure acting upon the ends of the cylinder D and on the part of the cap surrounding it, is balanced as far as is desirable by the steam in the cavities j, j, acting below the valve and cap.

We do not confine ourselves to the particular form of the valve or arrangement of the ports further than is necessary to the within described operation; but

What we claim and desire to secure by Letters Patent is—

15 Giving to the valve the whole or part of

the movement necessary to effect the change in the direction of the engine piston, by means of the steam acting upon a piston E which is arranged and applied to work perpendicularly to the valve within a cylinder D, attached to a cap fitted to the back of the valve, and is supported against the pressure of the steam by a rocker e, or its equivalent by which it is caused to operate substantially as herein set forth.

WM. H. GUILD.

WILLIAM F. GARRISON.
